UNITED STATES PATENT OFFICE

156,955

HAMBURGER MOLD OR THE LIKE

Rodney E. Graves, Williams, Ariz.

Application July 26, 1948, Serial No. 147,785

Term of patent 14 years

(Cl. D44—29)

To all whom it may concern:

Be it known that I, Rodney E. Graves, a citizen of the United States, residing at Williams, county of Coconino, State of Arizona, have invented a new, original, and ornamental Design for a Hamburger Mold or the like, of which the following is a specification, reference being had to the accompanying drawings, forming a part thereof.

In the drawings:

Fig. 1 is a perspective view of a hamburger mold or the like, showing my new design;

Fig. 2 is a transverse section on the line 2—2, Fig. 1.

I claim:

The ornamental design for a hamburger mold or the like, substantially as shown.

RODNEY E. GRAVES.
